UNITED STATES PATENT OFFICE

112,084

DESIGN FOR A LAMP

Donald L. Moore, Racine, Wis.

Application May 16, 1938, Serial No. 77,205

Term of patent 7 years

To all whom it may concern:

Be it known that I, Donald L. Moore, a citizen of the United States, of Racine, in the county of Racine and State of Wisconsin, have invented a new, original, and ornamental Design for a Lamp, of which the following is a specification, reference being had to the accompanying drawing, forming part thereof.

I claim:

The ornamental design for a lamp, as shown.

DONALD L. MOORE.
